UNITED STATES PATENT OFFICE.

ANTHONY C. McGINTY, OF LOS ANGELES, CALIFORNIA.

BABY-CARRIER.

1,330,485.

Specification of Letters Patent. Patented Feb. 10, 1920.

Application filed March 24, 1919. Serial No. 284,803.

To all whom it may concern:

Be it known that I, ANTHONY C. McGINTY, a citizen of the United States, residing at Los Angeles, in the county of Los Angeles and State of California, have invented new and useful Improvements in Baby-Carriers, of which the following is a specification.

My object is to make a baby carrier, and 10 my invention consists of the novel features herein shown, described and claimed.

Figure 1 is a perspective of a baby carrier embodying the principles of my invention.

Fig. 2 is a plan view of the baby carrier box removed from the harness unfolded and spread out flat, parts being broken away to show the construction.

Fig. 3 is a top plan view of the baby carrier shown in Fig. 1.

20 Fig. 4 is a fragmentary sectional detail on the line 4—4 of Fig. 3.

Fig. 5 is a fragmentary side elevation and looking in the direction indicated by the arrow 5 in Fig. 3.

25 The baby carrier box 1 consists of the seat 2, a back 3 hinged to the rear edge of the seat, the sides 4 and 5 hinged to the back 3 and adapted to extend along the sides of the seat 2, the foot rest support 6 hinged to 30 the front edge of the seat 2, and the foot rest 7 extending from the lower edge of the support 6.

The seat 2 consists of a rectangular wire frame 8 covered with a suitable heavy stiff 35 fabric 9. In a like manner the back 3 consists of a rectangular frame 10 and a fabric cover 11. The sides 4 and 5 consist of frames 12 and 13 and covers 14 and 15. The frame 8 is hingedly connected to the frame 40 10 by hooking one wire around another, and in a like manner the frames 12 and 13 are hingedly connected to the frame 10. Eyes 45 16 and 17 are formed at the outer lower corners of the frames 12 and 13 to engage hooks 18 and 19 formed at the outer front corners of the frame 8. The foot rest support 6 comprises a frame 20 and a cover 21, and the frame 20 is hingedly connected to the frame 8 by hooking one wire around another. The foot rest 50 7 is formed by bending the frame 20 at right angles and extending the cover 21 to cover the foot rest 7.

When the baby carrier box 1 is made up for use, as in Fig. 1, hooks 22 and 23 extend 55 from the front edges of the sides 4 and 5, and chains 24 and 25 are secured to the lower

corners of the foot rest support 6 to engage the hooks 22 and 23 and hold the foot rest from swinging backwardly. A chain 26 connects the front upper corners of the sides 4 and 5 to hold the baby upon the seat 2, said chain being detachable at either, or both ends, and the chain 27 extends from the center of the chain 26 to which a suitable toy may be attached for the amusement of the baby. The harness 28 is adapted to 60 secure the baby carrier box 1 to the body of the attendant and comprises a belt 29 adapted to be secured around the waist, a strap 30 connected at the central portion of the belt and adapted to pass over one shoulder and be attached to the front of the belt, a box support 31 removably connected to the belt and adapted to engage the box, and the chain 32 connected to the upper part of the 70 back 3 and extending along the strap 30 to the front. The belt 28 has a buckle construction 33 at the front, and the strap 30 has a buckle construction 34 at the front. The chain 32 slides through loops 35 upon the 75 belt 30 and has a hook 36 removably engaging an eye 37 at the center of the upper edge of the back 3, so that by manipulating the chain 32 from the front the box may be 80 adjusted to have the back 3 of the box fit the 85 back of the baby tender as desired.

The box support 31 is a spring wire and has a hook 38 at one end to engage a loop 39 upon the belt 29, and a hook 40 at the other end to engage the loop 41 upon the 90 belt. The box support 31 extends from a position to have the box 1 directly behind the attendant to a position to allow the box 1 to slide around to the side of the attendant. The wires forming the frame 10 are bent to 95 form posts 42 and 43 and bearings 44 and 45. The posts 42 and 43 fit in the loops 46 and 47 fixed to the belt 29 so as to hold the box 1 directly behind the attendant with the back 3 against the back of the attendant, and the box support 31 slides through the 100 bearings 44 and 45, so that when desired the box may be raised slightly to move the posts 42 and 43 out of the loops 46 and 47, so that the box may slide around the wire 31 to the side of the attendant, and so that the attendant may give attention to the baby in the box.

When it is desired to remove the box 1 from the harness 28 the hooks 38 and 40 may 110 be removed from the loops 39 and 41, the posts 42 and 43 may be removed from the

loops 46 and 47, and the hook 36 disconnected from the eye 37.

Various changes may be made without departing from the spirit of my invention as 5 claimed.

I claim:

1. A baby carrier comprising a box having a seat, a back hinged to the rear edge of the seat, sides hinged to the back and adapted to extend along the sides of the seat, a foot rest support hinged to the front edge of the seat, and a foot rest extending from the lower edge of the support; and a harness adapted to secure the box to the body of an attendant and having a belt adapted to be secured around the waist, a strap connected at the central portion of the belt and adapted to pass over one shoulder and be attached to the front of the belt, 10
- 15

a box support removably connected to the 20 belt and adapted to engage the box, and a chain connected to the upper part of the box back and extending along the strap to the front.

2. In a baby carrier, a box having a seat, 25 a back hinged to the rear edge of the seat, sides hinged to the back and adapted to extend along the sides of the seat, a foot rest support hinged to the front edge of the seat, a foot rest extending from the lower edge 30 of the support, and chains connecting the lower part of the foot rest support to the front parts of the sides; and a harness for securing the box to the body of an attendant.

In testimony whereof I have signed my 35 name to this specification.

A. C. McGINTY.
